Primary Examiner — Robin V Webster(74) *Attorney, Agent, or Firm* — Carter, DeLuca, Farrell & Schmidt LLP(57) **CLAIM**

The ornamental design for a grill cleaning tool, as shown and described.

DESCRIPTION

FIG. 1 is a perspective view of a grill cleaning tool in accordance with the present design;

FIG. 2 is a right side elevational view thereof;

FIG. 3 is a left side elevational view thereof;

FIG. 4 is a top plan view thereof;

FIG. 5 is a bottom view thereof;

FIG. 6 is a front elevational view thereof; and,

FIG. 7 is a rear elevational view thereof.

The broken line showings form no part of the claimed design.
